CLAIM

The ornamental design for a self-inclining display tray, as shown and described.

DESCRIPTION

FIG. 1 is an isometric view from the front, top and one side, of a first embodiment of a self-inclining display tray showing my new design;

FIG. 2 is a bottom plan view thereof;

FIG. 3 is a side elevational view thereof, the opposite side being a mirror image thereof;

FIG. 4 is a front elevational view thereof;

FIG. 5 is a rear elevational view thereof;

FIG. 6 is an isometric view thereof from the front, top and one side, with the bottom support folded upwardly, and with a storage box illustrated in broken lines for purposes of illustration only and forming no part of the claimed design;

FIG. 7 is an isometric view from the front, top and one side, of a second embodiment of a self-inclining display tray showing my new design;

FIG. 8 is a bottom plan view of FIG. 7;

FIG. 9 is a side elevational view of FIG. 7, the opposite side being a mirror image thereof;

FIG. 10 is a front elevational view of FIG. 7;

FIG. 11 is a rear elevational view of FIG. 7; and,

FIG. 12 is an isometric view of FIG. 7 from the front, top and one side, with the bottom support folded upwardly, and with a storage box illustrated in broken lines for purposes of illustration only and forming no part of the claimed design.
